US00D650515S

(12) **United States Design Patent**
Bradley, Jr. et al.

(10) **Patent No.:** **US D650,515 S**
(45) **Date of Patent:** **** Dec. 13, 2011**

(54) **LIGHT FIXTURE REFLECTOR**

(75) Inventors: **Aubrey Ray Bradley, Jr.**, La Habra, CA (US); **Robert Gordon Andersen**, Laughlin, NV (US)

(73) Assignee: **Growlite, Inc.**, Whittier, CA (US)

(**) Term: **14 Years**

(21) Appl. No.: **29/391,780**

(22) Filed: **May 12, 2011**

(51) **LOC (9) Cl.** **26-99**

(52) **U.S. Cl.** **D26/118**

(58) **Field of Classification Search** **D26/38, D26/36, 46, 73, 76, 81, 84, 88, 118, 138, D26/120, 13, 154, 155, 145, 86, 87, 85, 142, D26/61, 24, 93, 92, 153, 91, 89, 74, 121, D26/122, 71, 110, 105, 111, 131, 83, 80, D26/1, 2, 3, 4, 5, 26, 123, 125, 128, 63, 62, D26/64, 65, 41, 69, 139, 152, 150, 151, 141, D26/143, 144, 51, 140; 362/269, 648, 238, 362/111, 105, 86, 373, 294, 362, 297, 346, 362/341, 356, 352, 433, 404, 235, 240, 249.01-249.11, 362/321, 287, 374, 427, 190, 281, 324, 272, 362/244, 555, 147, 348, 263, 350; D10/11, D10/114.1; D22/108; 42/146, 117, 114, 42/115, 116, 142, 1.01; 439/110; 403/92, 403/97; 285/69, 78, 65; 257/89; D16/221; D13/110, 133, 134, 179, 180, 182; 160/332; D11/90, 89, 121, 125, 131; D25/119, 124, D25/125, 138; D23/386; D8/373, 354, 349, D8/389, 382, 363, 356, 377**

(57) **CLAIM**

The ornamental design for a light fixture reflector, as shown and described.

DESCRIPTION

FIG. 1 is an illustration of a perspective view of the light fixture reflector within a preferred environment.

FIG. 2 is an illustration of a front view of the light fixture reflector.

FIG. 3 is an illustration of a back view of the light fixture reflector.

FIG. 4 is an illustration of a right side view of the light fixture reflector.

FIG. 5 is an illustration of a left side view of the light fixture reflector.

FIG. 6 is an illustration of a top side view of the light fixture reflector; and,

FIG. 7 is an illustration of a bottom side view of the light fixture reflector.

The broken lines shown in the drawings illustrating unclaimed environmental structures form no part of the claimed design.

1 Claim, 7 Drawing Sheets
